ATTORNEY

UNITED STATES PATENT OFFICE.

HERMAN SCHLAICH, OF LONG ISLAND CITY, NEW YORK.

SPARK PLUG.

Application filed July 1, 1926. Serial No. 118,819.

This invention relates to spark plugs and is in the nature of an improvement upon the spark plug shown in my pending application Serial No. 103,200, filed April 20, 1926, entitled Spark plugs and spark intensifiers.

In said pending application disclosure is made of a spark plug in which one of the electrodes is carried on a thermally responsive element, the arrangement being such that the 10 sparking terminals are located close together when the motor is cold and are moved apart to lengthen the spark gap as the motor warms up. As therein illustrated, the thermally responsive element consists of a bi-metallic strip mounted on the lower margin of the 15 spark plug body and projecting downward therefrom.

It is an object of the present invention to provide a spark plug of this general character, in which it is impossible for the thermally responsive element or the sparking terminal carried thereby to become sufficiently heated to cause pre-ignition when the motor is otherwise in normal condition.

It is a further object of the invention to so construct the spark plug that the sparking gap can never exceed a predetermined length.

In the accompanying drawings forming a part of this specification:

Figure 1 is a sectional elevation of the spark plug; and

Figure 2 is a bottom plan view thereof.

The spark plug comprises a sleeve or body portion 1 threaded at its lower end for securement to a cylinder of an internal combustion engine. A porcelain insulator 2 is seated in this body portion, being held therein by an externally threaded sleeve nut 3. A conductive wire extends centrally through the insulator sleeve from a binding terminal 4 at the upper end of the insulator and terminates at its lower end in a central, fixed sparking terminal 5. A second sparking terminal 6 is carried by a thermally responsive element 7 45 consisting of a bi-metallic strip composed of metals having different co-efficients of expansion, said strip being formed as an arc of a volute spiral.

It is a point that this bi-metallic strip is mounted to lie within the lower end of the metallic body portion 1 of the spark-plug. For this purpose said body portion 1 of the spark plug is provided with a smooth-walled, circular internal rabbet or recess 8 at its lower 55 end. The bi-metallic strip has outwardly projecting, integral fingers 9 which are passed

outward through openings in the lower end of the spark plug body 1 and clinched at the outer side of said body.

The arrangement is such that when the motor is cold, the bi-metallic strip is out of contact with the spark plug body except at the end thereof which is attached to said body. The bi-metallic strip, however, lies within the body in position to engage it when expanded by the heat.

With the construction described, the sparking gap is quite short upon the starting of a cold motor, so that the spark may pass freely, even though the potential of the spark plug 70 current is low, due to slow rotation of the generator. As the motor warms up, the bi-metallic strip is caused to expand, so that the sparking terminal 6 is carried away from the fixed terminal 5 and the length of the spark- 75 ing gap is increased.

It is very important that heating of the bi-metallic strip to a temperature which would cause pre-ignition of the gases be avoided. It is primarily for the purpose of guarding 80 against such faulty operation that the bi-metallic strip is mounted within the body of the spark plug. By such mounting, the bi-metallic strip is caused to expand into contact throughout its entire length with the body 1 85 before a temperature of the bi-metallic strip has been reached at which pre-ignition would be caused to occur. Since the spark plug body 1 is in contact with a water-cooled part of the motor, it is always maintained at a 90 safe operating temperature and is also effective to control and limit the temperature of the bi-metallic strip when the bi-metallic strip moves into contact with it.

The mounting of the bi-metallic strip within the body of the spark plug has the further advantage that it is impossible for a careless car owner or mechanic to distort the bi-metallic strip more than a predetermined, limited 95 distance when attempting to clean the spark 100 plug or to adjust the spark gap.

Such mounting has the still further advantage of positively limiting the length of the spark gap, so that the passage of the spark when the motor is warmed up cannot, under 105 any circumstances, be interfered with.

Variations may be resorted to within the scope of the invention and parts of the improvements may be used without others.

I claim:

1. In a spark plug for internal combustion motors, the combination with a spark plug

body designed to engage a water-cooled part of the motor, of a fixed sparking terminal, a second sparking terminal spaced therefrom, and a thermally responsive element carrying 5 the second sparking terminal, said thermally responsive element being mounted on the spark plug body and being movable by heating into contact with the spark plug body throughout substantially its entire length before it has been heated to an excessive temperature sufficient to ignite the gases, whereby such excessive heating is avoided.

2. In a spark plug, the combination with a heat dissipating spark plug body, of an arcuate, bi-metallic strip mounted within the body, a sparking terminal carried by said bi-metallic strip, said sparking terminal being movable by the bi-metallic strip in response to temperature changes, and said bi-metallic 20 strip being movable to contact the spark plug body at a temperature below that at which pre-ignition would occur and being conformable in shape to said body at such temperature so that a large area of the bimetallic strip 25 directly engages the heat dissipating body.

3. In a spark plug, the combination with a spark plug body, of a fixed sparking terminal, a movable sparking terminal, and thermally responsive means mounted on the body 30 and carrying the movable sparking terminal, said spark plug body and thermally responsive means being relatively arranged to have extensive contact as the temperature rises and to arrest movement of the movable sparking terminal away from the fixed sparking terminal whereby the length of the spark gap is limited.

4. In a spark plug, the combination with a fixed sparking terminal, of a second sparking 40 terminal, a thermally responsive element carrying the second sparking terminal and a heat dissipating shell supporting and surrounding the thermally responsive element and engageable therewith over an extended 45 area upon a predetermined distortion thereof

to prevent heating of said element to the ignition temperature, and thereby to maintain the motor in efficient operation.

5. In a spark plug, in combination, a fixed 50 sparking terminal, an arcuate second sparking terminal, a thermally responsive element disposed in a plane transverse to the axis of the spark plug and carrying the second 55 sparking terminal said element being distortable by heating to carry the second sparking terminal away from the first, and means surrounding the thermally responsive element and engageable over an extensive area therewith for arresting distortion thereof to limit the length of the spark gap and the heating 60 of the element.

6. In a spark plug, in combination a fixed 65 sparking terminal, a second sparking terminal, an arcuate thermally responsive element disposed in a plane transverse to the axis of the spark plug and carrying the second 70 sparking terminal said element being distortable by changes in temperature to move the second sparking terminal toward and from the first in a direction transverse to the 75 spark plug axis, and a guard surrounding the thermally responsive element to prevent injury thereto and to limit distortion thereof by heating.

7. In a spark plug, in combination, a first 75 sparking terminal, a second sparking terminal, a thermally responsive element carrying the second sparking terminal and distortable by changes in temperature to move the second 80 sparking terminal toward and from the first, and heat dissipating means normally engaging a limited area of the element but arranged, upon a predetermined heating of the thermally responsive element, to engage 85 an extensive area thereof to prevent heating to the ignition temperature.

In testimony whereof I have affixed my signature to this specification.

HERMAN SCHLAICH.

CERTIFICATE OF CORRECTION.

Patent No. 1,714,521.

Granted May 28, 1929, to

HERMAN SCHLAICH.

It is hereby certified that error appears in the printed specification of the above numbered patent requiring correction as follows: Page 2, line 50, claim 5, strike out the words "an arcuate" and insert instead the article "a", and line 51, strike out the article "a" and insert instead the words "an arcuate"; and that the said Letters Patent should be read with these corrections therein that the same may conform to the record of the case in the Patent Office.

Signed and sealed this 2nd day of July, A. D. 1929.

body designed to engage a water-cooled part of the motor, of a fixed sparking terminal, a second sparking terminal spaced therefrom, and a thermally responsive element carrying 5 the second sparking terminal, said thermally responsive element being mounted on the spark plug body and being movable by heating into contact with the spark plug body throughout substantially its entire length before it has been heated to an excessive temperature sufficient to ignite the gases, whereby such excessive heating is avoided.

2. In a spark plug, the combination with a heat dissipating spark plug body, of an arcuate, bi-metallic strip mounted within the body, a sparking terminal carried by said bi-metallic strip, said sparking terminal being movable by the bi-metallic strip in response to temperature changes, and said bi-metallic 20 strip being movable to contact the spark plug body at a temperature below that at which pre-ignition would occur and being conformable in shape to said body at such temperature so that a large area of the bimetallic strip 25 directly engages the heat dissipating body.

3. In a spark plug, the combination with a spark plug body, of a fixed sparking terminal, a movable sparking terminal, and thermally responsive means mounted on the body 30 and carrying the movable sparking terminal, said spark plug body and thermally responsive means being relatively arranged to have extensive contact as the temperature rises and to arrest movement of the movable sparking terminal away from the fixed sparking terminal whereby the length of the spark gap is limited.

4. In a spark plug, the combination with a fixed sparking terminal, of a second sparking 40 terminal, a thermally responsive element carrying the second sparking terminal and a heat dissipating shell supporting and surrounding the thermally responsive element and engageable therewith over an extended 45 area upon a predetermined distortion thereof

to prevent heating of said element to the ignition temperature, and thereby to maintain the motor in efficient operation.

5. In a spark plug, in combination, a fixed 50 sparking terminal, an arcuate second sparking terminal, a thermally responsive element disposed in a plane transverse to the axis of the spark plug and carrying the second 55 sparking terminal said element being distortable by heating to carry the second sparking terminal away from the first, and means surrounding the thermally responsive element and engageable over an extensive area therewith for arresting distortion thereof to limit the length of the spark gap and the heating 60 of the element.

6. In a spark plug, in combination a fixed 65 sparking terminal, a second sparking terminal, an arcuate thermally responsive element disposed in a plane transverse to the axis of the spark plug and carrying the second 70 sparking terminal said element being distortable by changes in temperature to move the second sparking terminal toward and from the first in a direction transverse to the 75 spark plug axis, and a guard surrounding the thermally responsive element to prevent injury thereto and to limit distortion thereof by heating.

7. In a spark plug, in combination, a first 75 sparking terminal, a second sparking terminal, a thermally responsive element carrying the second sparking terminal and distortable by changes in temperature to move the second 80 sparking terminal toward and from the first, and heat dissipating means normally engaging a limited area of the element but arranged, upon a predetermined heating of the thermally responsive element, to engage 85 an extensive area thereof to prevent heating to the ignition temperature.

In testimony whereof I have affixed my signature to this specification.
